Corporation, a corporation of Pennsylvania

Application January 14, 1944, Serial No. 518,206

13 Claims. (Cl. 175—294)

1

The invention relates to a motor operated circuit breaker and control system therefor.

An object of the invention is the provision of an improved motor operated circuit breaker, of the trip-free type that is relatively simple, very compact, and relatively inexpensive to manufacture.

Another object of the invention is the provision of a trip-free circuit breaker with an improved motor operating means for closing the circuit breaker embodying means for automatically resetting the circuit-breaker mechanism following tripping of the circuit breaker.

Another object of the invention is the provision of a trip-free circuit breaker with an improved motor operating means for closing the breaker, said motor operating means having a resetting mechanism operable to automatically reset the circuit-breaker mechanism and the motor operated closing means following tripping of the circuit breaker.

Another object of the invention is the provision of a trip-free circuit breaker with an improved motor operating mechanism embodying a relatively compact spring means automatically operative to reset the breaker mechanism following tripping of the breaker.

Another object of the invention is the provision of an improved motor operated circuit breaker as described in the preceding paragraph, wherein the resetting spring is connected in a novel manner between the breaker operating lever and the motor operated closing lever so that the resetting moment of the spring applied to the breaker operating lever increases as it approaches the end of the resetting stroke to provide sufficient force to reset the circuit-breaker latching means.

Another object of the invention is the provision of a trip-free circuit breaker with a motor operating means and a novel and improved anti-pump control system therefor.

Another object of the invention is the provision of a trip-free circuit breaker with a motor operating means and an improved anti-pump control system which does not require a motor contactor and relay.

Another object of the invention is to provide a circuit breaker with an improved power operated closing mechanism wherein a spring is operable upon release of the breaker mechanism to effect a resetting operation of the breaker mechanism, said spring applying its force through a greater moment at the end of the resetting stroke than at the start of the stroke.

Another object of the invention is to provide a circuit breaker having means for automatically resetting the breaker mechanism following a trip-

2

ping operation with improved motor operated closing mechanism wherein energization of the closing motor is controlled by a drum switch operated by the motor.

- 5 Another object of the invention is to provide a circuit breaker having a supporting frame for the breaker mechanism with a motor operated closing means, said motor and closing means being rigidly mounted on the supporting frame in front of the breaker mechanism to maintain the correct relation between said closing means and the breaker mechanism and to provide a very compact structure of relatively small vertical and horizontal dimensions.
- 10 15 The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawings, in which:

Figure 1 is a side elevational view, partly in section, of a circuit breaker embodying the invention,

25 Fig. 2 is an elevational view similar to Fig. 1 but showing the breaker in the tripped open and reset position, and

30 Fig. 3 is a diagrammatic view of the electrical circuits and apparatus embodying the invention.

Referring to Figure 1 of the drawings, the reference numeral 11 designates a base of strong insulating material which supports the various parts of the circuit breaker. A pair of terminals 13 and 15 are suitably secured to the base and each terminal has one or more connecting studs 19 which extend through the back of the base 11 and serve to electrically connect the breaker to the circuit which it controls.

40 The upper terminal 13 has a contact block 21 of rigid conducting material secured thereto; and a rigid contact block 23 secured to the base is electrically connected to the lower terminal 15 through the energizing winding of the trip device of the breaker, which will be hereinafter described.

45 The contact means and mechanism of the circuit breaker illustrated are similar to the circuit breaker fully disclosed in Patent No. 2,214,471 issued September 10, 1940 to Leon R. Ludwig and Merl E. Horn, and assigned to the assignee of the present invention. Hence only a brief description of these parts will be given in this application.

The main stationary contacts 25 and 27 are rigidly secured to the contact blocks 21 and 23, respectively; and the auxiliary stationary contacts 29 and 31 are secured to a triangularly-shaped contact platform 33 of conducting material which is mounted on the upper portion of the block 21 for limited tilting and rocking movement by means of pins 35 projecting from the opposite sides of the platform which engage in slots 37 provided in a pair of side walls 39 secured to the block 21. The platform 33 is biased outwardly from the base 11 by a plurality of springs 41 and 43, and outward movement of the platform is limited by the engagement of the pins 35 with the outer ends of the slots 37 and by stop projections 45 carried by the platform adjacent its upper end. The platform 33 and, consequently, the auxiliary contacts 29 and 31 are electrically connected to the terminal 13 by means of a flexible shunt conductor 47.

The movable contact means of the circuit breaker comprises a channel-shaped contact arm 49 of conducting material which is rigidly secured to a pivoted switch member 51 by means of a plurality of screws 53. The contact arm 49 carries a main contact bridging member 55 for bridging the main contacts 25 and 27, and an auxiliary contact member 57 for engaging the stationary auxiliary contacts 29 and 31, the auxiliary contact member 57 being secured to the upper end of the channel-shaped contact arm 49 by a plurality of screws 59.

The main contact bridging member 55 is formed of rigid conducting material, and is loosely mounted on the contact arm 49 for limited movement relative to the contact arm toward and away from the main contacts 25 and 27 by means of a pair of studs 61 secured to the contact carrying arm 49, only one stud being shown. A pair of coil springs (not shown) encircle the studs 61, and are disposed between the contact carrying arm 49 and the bridging member 55 for biasing the bridging member toward the stationary main contacts 25 and 27 with a predetermined force. The ends of the bridging member 55 are beveled to lie parallel with the beveled edges of the contact blocks 21 and 23, and have a pair of contacts 67 secured thereto for engaging the main stationary contacts 25 and 27.

The auxiliary contact member 57 is formed of rigid conducting material, and has an intermediate contact 69 and an arcing contact 71 secured thereto for engaging the intermediate and arcing contacts 29 and 31 of the stationary contact means.

A flexible shunt conductor 73 electrically connects the auxiliary contact arm 49 to the main stationary contact block 23. The flexible conductor 73 has its upper end secured to the contact arm 49 by the bolts 53. The lower end of the flexible shunt conductor 73 is secured to the lower contact block 23 by means of a bolt 77.

The switch member 51 has a yoke-shaped lower end which is pivotally mounted between the side walls of a main frame 79 by means of the pivot pin 81. The switch member 51 is movable about its pivot axis to open and closed circuit positions to open and close the contact means of the breaker by means of an operating mechanism indicated generally at 83.

The operating mechanism 83 is supported by the main frame 79 and comprises an actuating lever 85 pivoted on a pin 87 carried by the frame, and is connected to the switch member 51 by a link 89. An operating member 91 is also pivoted

on the pin 87 for movement about the same axis as the actuating lever 85. The actuating lever 85 is normally releasably connected to the operating member 91 for movement thereby by means of a pair of latches 93 and 95, which are pivotally mounted on the lever 85 at 97 and 99, respectively. The latches 93 and 95 are biased to latching position by springs 96 and 98, respectively. The latch 93 engages a roller 101 carried by the operating member 91, and this latch is, in turn, held in latching position by the auxiliary latch 95. The operating member 91 is adapted to be releasably held in closed circuit position by means of a main holding latch 103 pivoted at 109, which releasably engages the roller 101. The auxiliary latch 95 is provided with a curved tailpiece 105 disposed to one side of the latch 93 by means of which it is released to cause release of the latch 93 and consequent tripping of the circuit breaker by the release of the actuating lever 85 from its connection with the operating member 91. When released the actuating member 85 moves in a counterclockwise direction about the pivot axis 87 independently of the operating member 91, causing opening of the movable contact means. During this movement, a cam surface 107 of the lever 85 engages the rounded nose of the main holding latch 103, moving the holding latch to released position to effect release of the operating member 91. The switch member 51 and the actuating lever 85 are biased to open position by means of a pair of accelerating springs 109 (only one being shown), which are connected at their upper ends to the switch member 51 and at their lower ends to the sides of the main frame 79.

To close the circuit breaker after it has been tripped open, the operating member 91 is first moved in a counterclockwise direction about the pivot axis 87 to the open position to effect resetting of the latches and reestablishment of the releasable rigid connection between the actuating lever 85 and the operating member 91. After the rigid connection is thus established, the operating member 91 is moved in a clockwise direction to closed position by means of a motor operated closing mechanism indicated generally at 111 to effect closing of the contact means of the breaker. The clockwise or closing movement of the operating member 91 is limited by a portion 92 thereof striking a fixed stop 94 on the frame 79. When the parts have been moved to closed position, the main holding latch 103 reengages the roller 101 to hold the operating member in closed position. The stop 94 is located to permit a slight overtravel of the member 91 to insure proper engagement of the latch 103 with the roller 101. It will be noted that the construction of the operating mechanism is such that the movable contact means is trip-free of the operating member 91; that is, when the breaker is tripped, the contact means move to open position irrespective of the position of the operating member 91.

The mounting arrangement of the contact means is such that during opening of the breaker 65 the main bridging member 55 is first separated from the stationary contacts 25 and 27, while the auxiliary contacts remain in engagement by reason of the outward movement of the contact platform 33 under the influence of the biasing springs 41 and 43. After the bridging member 60 55 has separated a predetermined distance from the main stationary contacts, the intermediate contacts 29 and 69 begin to separate. This takes place as soon as the pins 35 engage the ends of 70 the slots 37. During this time, the arcing con-

tacts 31 and 71 remain in engagement due to the rocking movement of the contact platform 33. After the intermediate contacts have separated a predetermined distance, the arcing contacts 31 and 71 begin to separate. During closing, the contacts engage in the reverse order, as will readily be understood. It will thus be seen that the arc formed during separation of the contacts is drawn only between the arcing contacts 31 and 71.

The circuit breaker is adapted to be tripped open either manually, or automatically, in response to predetermined overload conditions in the circuit, by means of a trip device indicated generally at 115.

The trip device comprises a trip lever 117 which is pivotally mounted intermediate its ends on the frame 79 by means of a pivot pin 119, and an electromagnet, indicated generally at 121, which is operable in response to the predetermined overload conditions to move the trip lever 117 to tripping position to cause automatic opening of the circuit breaker.

One arm 123 of the trip lever 117 is offset and extends inwardly toward the base 11 of the circuit breaker, and has its inner end disposed immediately above the electromagnet 121 to be engaged and moved by a plunger of the electromagnet to effect automatic tripping of the breaker. The arm 123 of the trip lever is provided with a projection 125 which is adapted to engage the curved tailpiece 105 of the auxiliary latch 95 to move this latch to released position upon movement of the trip lever to tripping position. The other arm of the trip lever 117 forms a handle 127 whereby the trip lever may be manually moved to tripping position to effect manual opening of the circuit breaker. A spring 129 connects the arm 123 of the trip lever 117 to an extension of the main holding latch 103 so that the spring thus serves to bias the main holding latch to latching position and the trip lever to its normal inoperative position, as shown in Fig. 1.

The electromagnet 121 comprises a stationary core member 131, a movable armature 133 having a trip rod 135 thereon, and an energizing winding 137 having one end connected to the contact block 23 and the other end connected to the terminal 15.

Upon the occurrence of an overload of a predetermined value, the electromagnet 121 is energized a sufficient amount to attract the armature 133 and thrust the trip rod 135 upwardly to trip the breaker. When the armature 133 is attracted the upper end of the trip rod engages the arm 123 of the trip lever 117 and actuates the latter to effect opening of the contacts in the previously described manner.

The circuit breaker is closed by means of the power operated mechanism 111. The closing mechanism comprises a motor 139 rigidly supported on a casting 141 having a base 143 of insulating material secured thereto. The insulating base is, in turn, rigidly secured by means of bolts 145 to the main frame 79 of the breaker. The casting 141 forms a housing for a reduction gearing (not shown) through which the motor 139 drives a crank arm 147. The crank arm is rigidly mounted on a shaft 149 for rotation therewith, the shaft being mounted for rotation in bearings (not shown) suitably supported in the casting 141. Pivotally mounted on a pin 151 supported in the casting 141 and in a yoke portion 153 integral with the casting is a closing lever 155 which is connected by

means of a link 157 to the operating member 91. The link 157 is connected to the lever 155 by means of an adjusting rod 159 which threadedly engages the lower end of the link and is locked in position by a lock nut 161. The lower end of the rod 159 is pivotally connected to the lever 155 by a pivot pin 163 supported in the bifurcated end of the lever. The other end of the link 157 is pivotally connected by means of a pivot pin 165 to a bracket 167 rigidly secured to an insulating block 169. The block 169 is secured to the operating member 91. A spring 171 compressed between the closing lever 155 and a projection 173 extending from the upper end of the link 157 is disposed to bias the bracket 167 and the operating member 91 in a counterclockwise resetting direction about the pin 87. The spring 171 is retained in telescopic tubes 175 and 177 which are pivotally connected by means of pins 179 and 181 respectively to the closing lever 155 and the projection 173 of the link 157. The spring 171 is compressed between a stop 183 (Fig. 1) in the tube 175 and a similar stop 185 in the tube 177. The force of the spring 171 biases the closing lever 155 and the link 157 in opposite directions about the pivot pin 163, but since the lever 155 is mounted on the fixed pivot 151 and the link 157 is connected to the operating member 91, the force of the spring acting through the link 157 biases the operating member 91 in a counterclockwise direction about the pivot 87. The member 91 is normally held against movement in this direction by the latch 103 cooperating with the roller 101 on the member 91.

When an overload of predetermined magnitude occurs, the trip magnet 121 operates the latch 95 to release the actuating lever 85 from the operating member 91 and permit the springs 109 to open the contacts. As was previously described, during the opening movement of the actuating lever 85, the surface 107 engages and operates the latch 103, thus releasing the operating member 91. The member 91 is immediately actuated counterclockwise to resetting or relatching position (Fig. 2) by the spring 171 in order to reset the latches 93 and 95 and to reconnect the operating member 91 to the actuating member 85. The relatching occurs during the latter part of the counterclockwise travel of the operating member 91. The spring 171 continuously expands during the relatching movement of the mechanism, but the lever arm by which the force of the spring is applied to operate the operating member 91 in relatching or upward direction about the pivot 87 increases as the member 91 moves upwardly, thus increasing the spring force available for the relatching operation.

Referring to Fig. 1 which shows the breaker in the closed position, the spring 171 produces a moment about the pin 163 which tries to move the link 157 counterclockwise about pin 163 and to separate the pins 151 and 165. Since the link 157 is pivotally connected at 165 to the operating member 91, the pin 165 must follow a circular path about the fixed pivot 87. It will be noted that the pin 165 is over center to the right of a line indicated at A drawn through the centers 87 and 151. By extending the line of the force indicated at B, between pins 151 and 165, it may be seen that the position of the pin 165 provides a moment arm indicated at C with which the force produced by the spring 171 along the line B tends to move the operating member 91 counterclockwise about its

pivot 87. This movement is normally prevented by the latch 103 which restrains the member 91 in the position shown in Fig. 1. Upon release of the member 91 in the previously described manner, the member 91 rotates counterclockwise about its pivot 87 thus increasing the distance between the pins 165 and 151, permitting the spring 171 to expand. The spring 171 expands very slowly during the early part of the resetting movement since the pin 165 at the start of the movement is close to the line A. As the resetting movement progresses the spring 171 extends itself moving the operating lever 91 to the position shown in Fig. 2, and since the lever 91 is connected by means of the link 157 to the closing lever 155, this lever is moved therewith to its Fig. 2 position. It may be noted that while the link 157 is connected to the outer ends of the levers 91 and 155, the lower end of the spring 171 is connected to the lever 155 at a point approximately midway between the ends of the lever. Consequently, as the spring 171 expands and the upper end of the spring moves upwardly, the lower end of the spring follows but at a slower rate of speed. It may also be noted that as the resetting movement progresses the lever arm C progressively increases as indicated in Fig. 2, so that the reduced strength of the expanding spring 171 is applied through a greatly increased lever arm to produce a greatly increased torque on the lever 91 about the pivot 87 at the end of the resetting movement for resetting the latch mechanism.

After the latches 93 and 95 are reset and the actuating lever 85 is reconnected to the operating member 91, the closing lever 155 is operated by the motor mechanism from its Fig. 2 position to the position in which it appears in Fig. 1. During this movement the lever 155 acting through the link 157 moves the operating lever 91 and the actuating lever 85, which is now connected to the operating lever, clockwise about the pivot 87 to close the contacts. As previously set forth, the motor 139 rotates the crank arm 147 through the reduction gearing (not shown) encased in the housing 141. The crank arm 147 (Figs. 1 and 2) as a point near its free end carries a pin 187 upon which is rotatably mounted a roller 189. During the counterclockwise rotation of the crank arm 147, the roller 189 engages a formed over ear 191 extending laterally from the lever 155. The ear 191 normally lies out of the path of travel of the roller 189 (Fig. 1) but when the mechanism moves to the relatching position (Fig. 2) the ear 191 is moved to the Fig. 2 position where it is in the path of the roller 189. Upon rotation of the crank arm 147, the roller 189 engages the ear 191 and operates the lever 155 to close the breaker.

During the greater portion of the closing movement only a comparatively light load is imposed upon the motor. It is during the early part of the closing operation that most of the work of restressing the spring 171 is accomplished so that the major portion of the power of the motor is available to close the contact means during the latter portion of the closing stroke.

Referring now to the circuit diagram (Fig. 3), the conductors 193 and 195 are connected to a suitable source of electrical energy. The circuit 193-195 is connected to operate the motor 139 through a drum switch, a developed view of which is indicated generally at 197. The drum switch is secured on the crank arm shaft 149 for rotation therewith. The circuit for ener-

gizing the motor 139 is also controlled by an auxiliary switch, the contacts 199 of which are open when the breaker is closed and closed when the breaker is open. A manually operated switch 201 is provided for initiating a closing operation of the motor. The switch 201 has normally closed contacts 203 and normally open contacts 204 and 205 and is biased to the neutral position shown in Fig. 3 by springs 207. The drum switch 197 comprises a cylindrical conducting segment 209 mounted on and rotatable with a drum or cylinder 211 of insulating material. Five contact fingers 213, 215, 217, 219 and 221 are provided for cooperating with the segment 209 to control the circuits for energizing the motor 139. The contact finger 213 is connected by a wire 223, contact 203, switch 201 and a wire 225 to the conductor 193. The contact finger 215 is connected by means of a wire 227 through the auxiliary contacts 199 and a wire 229 to one terminal of the motor 139, the other terminal of the motor being connected directly to the conductor 195. A wire 231 connects the contact finger 217 directly to the conductor 193. The contact finger 219 is connected by means of a wire 233, through the normally open contacts 205, switch 201 and the wire 225 to the conductor 193.

The contact fingers at the end of a closing operation rest on the drum 211 in substantially the positions shown in Fig. 3 in relation to the conducting segment 209. In this position of the drum switch, a circuit is prepared to energize the motor and automatically reset the crank arm 147 (Fig. 1) and the drum switch upon opening of the breaker. This circuit extends from the conductor 193, over the wire 225, normally closed contacts 203, wire 223, contact fingers 213 and 215, at this time in contact with the portion 209a of the segment 209, wire 227, open auxiliary contacts 199 and wire 229 through the motor 139 to the conductor 195. This circuit is open at the auxiliary contacts 199 when the circuit breaker is closed. When the breaker is operated to the open position, in the previously described manner, the auxiliary contacts 199 close energizing the motor 139. The motor, operating through the reduction gearing (not shown), rotates the crank arm 147 in the direction of the arrow (Fig. 1) from the Fig. 1 position to approximately the position shown in Fig. 2. Since the crank arm 147 and the drum switch 197 are keyed to the same shaft, the drum switch is also rotated in the direction indicated by the arrow (Fig. 3). At the point indicated at 0° on the drum switch, the portion 209a of the segment passes from beneath the contact fingers 213 and 215, thus opening the circuit therethrough and deenergizing the motor. The motor, however, coacts a short distance before it stops thereby bringing a portion 209b of the switch segment under the contact fingers 219 and 221. This prepares a second motor energizing circuit extending from the conductor 193 over the wire 225, normally open contact 205 of the control switch 201, wire 233, contact fingers 219 and 221 and the segment portion 209b and the wire 229 through the motor to the conductor 195. This circuit is open at the contacts 201-205 and the motor remains unenergized until the switch 201 is operated to engage the contact 205. Closure of these contacts energizes the motor 139 over the circuit just described. The motor then operates the crank arm 147 in a counterclockwise direction from

the position shown in Fig. 2 to the Fig. 1 position. During this operation the roller 189 on the end of the crank arm engages the ear 191 of the closing lever 155 and operates this lever counterclockwise about the pivot 151 to close the breaker in the previously described manner. During the closing operation the segment 209 engages the contact finger 217 at the point indicated at 105° on the segment (Fig. 3). This engagement occurs before the circuit breaker starts to move toward closed position. This establishes a sealing circuit for the motor which shunts the control switch contacts 205 and maintains the motor running throughout the remainder of the closing cycle even if the manual switch 201 is released and the contacts 205 opened. At the point indicated at 240° on the segment 209, the segment separates from the contact fingers 217 and 221 and automatically opens the motor circuit. The motor coasts until the drum 211 comes to rest with the segment 209 in substantially the position indicated in Fig. 3 with relation to the contact fingers. In this position of the mechanism, the roller 189 on the crank arm 147 occupies a position slightly to the right and out of the path of movement of the ear 191 on the closing lever 155, as shown in Fig. 1, so that this lever is free to operate to relatch the operating lever 91 to the actuating lever 85 following the next circuit-breaker opening operation.

The circuit breaker is trip-free of the closing mechanism. That is, if the breaker is closed in against a fault, the breaker mechanism will be tripped and moved to the open contact position irrespective of the position of the closing mechanism or energized condition of the closing motor.

The shape of the segment 209 is such that the motor circuit through the contacts 205 will be opened before the breaker contacts touch and before the breaker reaches the closed position in order to prevent "pumping" if the breaker is closed against a fault with the manual switch 201 held in the position to maintain the contact 205 in closed position. Referring to Fig. 3, it will be noted that the segment 209 is shaped so as to disengage the contact finger 219 at the point designated at 210° or 30° before the segment disengages the contact fingers 217 and 221. This insures that the circuit through the contacts 205 will be opened and that the motor will be deenergized as soon as the segment 209 disengages the contact fingers 217 and 221. Since the contacts 203 are held open so long as the switch 201 is held down the previously described automatic resetting operation will not occur following a trip-free operation of the breaker since the motor energizing circuit through the contacts 203 and the contact fingers 213 and 215 will be open, consequently the motor cannot be energized again by holding the control switch 201 closed. Thus "pumping" of the breaker is prevented. When the switch 201 is released, the springs 207 restore it to its central position closing the contacts 203 and opening the contacts 205. Since, at this time, the segment 209 is in contact with the contact fingers 213 and 215, and the auxiliary contacts 199 closed when the breaker opened, the motor is energized to reset the mechanism crank to the position shown in Fig. 2 and the drum switch to the reset position. In this position, as previously set forth, the portion 209b of the segment 209 engages the fingers 219 and 221, so that upon closure of the contacts 205 the

motor will again be energized to close the breaker.

The control switch 201 may be located at a point remote from the circuit breaker, for instance, at a control station, and conventional signals such as lights or audible signal means, may be employed to indicate the condition of the breaker. The breaker may also be tripped open from a remotely located control station by operating the manual switch 201 (Fig. 3) into engagement with a contact 204 which, when closed, trips the breaker by means of a conventional shunt trip coil 237. The shunt trip coil is energized over a circuit extending from the conductor 193 over the wire 225, switch member 201, contact 204, a wire 239, auxiliary contacts 241 closed when the breaker is closed, a wire 243 and the shunt trip coil 237 to the conductor 195.

Having described the invention in accordance with the patent statutes, it is to be understood that various changes and modifications may be made in the structural details and combination of elements disclosed without departing from some of the essential features of the invention. It is, therefore, desired that the language of the appended claims be given as reasonably broad interpretation as the prior art permits.

We claim as our invention:

1. In a circuit breaker, a switch member movable to open and closed circuit positions, power operated means for moving said switch member to closed circuit position, an energizing circuit for said power means, trip means operable to cause opening movement of said switch member irrespective of said power operated means, an auxiliary switch disposed in said circuit to be open when the breaker is closed and closed when the breaker is open, said auxiliary switch being operative when closed to energize said power operated means, a drum switch operated by said power operated means connected in said circuit to control the energization of said power means, said drum switch having contact means thereon operative to open said circuit through said auxiliary switch and to prepare a circuit for energizing the power operated means independently of said auxiliary switch, a manually operable switch operative to initiate energization of said power operated means over said prepared circuit, said drum switch being thereafter operative to establish a circuit for energizing said power operated means independently of said auxiliary switch and said manual switch to cause movement of said switch member to closed circuit position and for automatically deenergizing said said power operated means at the completion of the closing movement of said power operated means.

2. In a circuit breaker, a switch member movable to open and closed circuit positions, motor operated mechanism operative at times to move said switch member to closed circuit position, trip means operative to cause opening movement of said switch member irrespective of said motor operated mechanism, an energizing circuit for said motor mechanism, an auxiliary switch disposed in said circuit to be open when the breaker is closed and closed when the breaker is opened, a manually operable control switch having two positions for controlling the energization of said motor, a drum switch operable by said motor mechanism, said drum switch having contact means thereon operative to effect energization of said motor over a first motor control circuit extending through said auxiliary switch

and a first position of said manual control switch, said drum switch having contact means thereon operative to prepare a second motor control circuit extending through a second position of said manual control switch but independently of said auxiliary switch and to automatically open said first motor control circuit, said manual control switch being movable to said second position to close said second circuit to initiate energization of said motor over said second circuit, and said drum switch being further operative to close a third motor control circuit independently of said auxiliary switch and said manual control switch and to open said third circuit at the completion of the closing movement of said mechanism.

3. In a circuit breaker, a switch member movable to open and closed circuit positions, operating mechanism for said circuit breakers, power operated means for actuating said operating mechanism to close the switch member, a circuit for energizing said power operated means, trip means operable to cause opening movement of said switch member irrespective of the power operated means, spring means for moving said operating mechanism to a reset position, an auxiliary switch in said circuit operated by said breaker and disposed to be open when the breaker is closed and closed when the breaker is open, said auxiliary switch being operative when closed to energize said power operated means, a drum switch operated by said power operated means having contact means thereon for controlling the energization of said power operated means, said drum switch being operative to deenergize the power operated means and to prepare a circuit for energizing the power operated means independently of said auxiliary switch, a manually operable switch in said circuit operative to initiate energization of said power operated means over said prepared circuit, said drum switch being thereafter operative to establish a circuit for energizing said power operated means independently of said auxiliary switch and said manual switch to cause movement of said switch member to closed circuit position and for automatically deenergizing said power operated means at the completion of the closing movement of said power operated means.

4. A circuit breaker comprising switch means movable to open and closed circuit positions, an operating member operable to move said switch means to closed position, means operable to effect opening of said switch means irrespective of the position of said operating member, a closing lever, means connecting said closing lever to said operating member for actuating said operating member to close said switch member, spring means connected at one end to said closing lever at a point substantially intermediate the ends thereof and at the other end to said connecting means applying a torque to said operating member for moving said operating member to a reset position and for moving said closing lever to an operative position, said operating member, said closing lever and said spring being adapted to increase the moment arm with which said torque is applied to provide a greater torque on said operating member near the end of a resetting operation than at the beginning of a resetting operation.

5. An operating mechanism for a circuit breaker comprising an operating member operable to close said breaker and movable from a closed position to a reset position, a pivoted closing lever, a link at all times connected to said oper-

ating member and to said closing lever, power means for engaging and moving said closing lever to said closed position to close said breaker, spring means compressed between said link and a point substantially intermediate the ends of said closing lever and cooperating with said parts to move said operating member to said reset position with a predetermined initial torque and for moving said closing lever to operative position free of said power means, and said parts being adapted to increase the moment of application of said torque to said operating member to increase the torque on said operating member near the end of said resetting movement.

6. An operating mechanism for a circuit breaker comprising an operating member movable to close said circuit breaker, said member being movable from a closed position to a reset position, a closing lever operable to move said operating member to close said breaker, a link at all times connecting said closing lever to said operating member, a spring compressed between said link and a point intermediate the ends of said closing lever to apply a predetermined initial torque biasing said operating member in resetting direction, said parts being adapted to increase the moment of application of said torque to apply increasing torque to said operating member during the entire movement of said member to reset position.

7. In a circuit breaker, a switch member movable to open and closed circuit positions, operating mechanism comprising an operating member operable to move said switch member to closed position, means operable to cause opening of the breaker, a closing lever, rigid means connecting said closing lever to said operating member, spring means having one end connected to said connecting means at a point adjacent to said operating member and the other end connected to said closing lever for moving said closing lever to an operative position and for moving said operating member to a reset position, said connecting means, said closing lever and said spring means being adapted to cause said spring means to apply a greater torque to said operating member near the end of a resetting stroke than at the beginning of said resetting stroke, power operated means operable when energized to actuate said closing lever to close said breaker, an energizing circuit for said power operated means, means comprising auxiliary contact means closed upon opening of said breaker and a drum switch for effecting initial energization of said power operated means to cause said power operated means to operate to a predetermined position, manually operated contact means in said circuit for initiating energization of said power means to effect closing of said breaker, and said drum switch being operated by said power means to thereafter control the energization of said power means independently of said manual contact means and said auxiliary contact means.

8. In a circuit breaker, operating mechanism comprising an operating member operable in one direction to close said breaker and in another direction to effect resetting of said mechanism, means operable to effect opening of said breaker, a closing lever, connecting means operatively connecting said closing lever and said operating member, spring means having one end connected to said closing lever at a point between the ends thereof and the other end connected to said connecting means to apply a torque to said operating member for moving said operating member in

resetting direction and for moving said closing lever to an operative position, said parts being adapted to increase the moment of application of said torque to said operating member during a resetting operation to produce a greater torque on said operating member near the end of a resetting stroke than at the start of said resetting stroke, and power operated means disposed to engage said closing lever when said lever is in said operative position and actuate said closing lever to close said breaker.

9. In a circuit breaker, a circuit controlling member biased to open circuit position, an operating member operable to close said breaker and movable to an open circuit position, latch means releasably connecting said controlling member to said operating member, means for releasably restraining said operating member in closed circuit position, electroresponsive means for operating said latch to effect release of said circuit controlling member and permit movement of said circuit controlling member to open position, said circuit controlling member when moved to open position actuating said restraining means to permit movement of said operating member to open position to relatch said operating member to said controlling member, a closing lever, means at all times connecting said closing lever to said operating member for unitary movement, spring means having one end connected to said closing lever at a point substantially intermediate the ends thereof and the other end connected to said connecting means, said spring means upon release of said operating member applying a force to said operating member to move said member to effect relatching of said operating member to said controlling member and to move said closing lever to an operative position, said operating member, said closing lever and said spring being adapted to increase the moment of application of said force to said operating member to apply an increasing torque on said operating member at the time said latch means relatches during said relatching movement, and power operated means for actuating said closing lever to move said controlling member to closed circuit position.

10. In a circuit breaker, a switch member movable to open and closed circuit positions, operating mechanism for said circuit breaker comprising an operating member operable to move said switch member to closed circuit position, means releasably connecting said switch member to said operating member, a closing lever, a link connecting said closing lever to said operating member, means for restraining said operating member and said switch member in closed circuit position, said restraining means also restraining said closing lever in an inoperative position, trip means operable in response to predetermined circuit conditions to release said switch member from said operating member to effect opening of said switch member, said switch member during said opening movement operating said restraining means to permit movement of said operating member to reset position to reconnect said operating member to said switch member, resetting spring means operable to effect a resetting operation of said operating member and to move said closing lever to an operative position, said spring means being disposed between said closing lever and said link to apply a torque to said operating member and adapted to increase said torque during the latter part of the resetting movement, motor means for operating said closing lever to close said breaker, means comprising an auxiliary

switch closed upon opening of said breaker and a drum switch for automatically effecting initial energization of said motor to cause said motor to operate to a predetermined position, a manual switch operable to effect energization of said motor to cause said motor to operate said closing lever and close said breaker, said drum switch being operated by said motor to thereafter automatically control the energization of said motor independently of said auxiliary switch and said manual switch.

11. An operating mechanism for operating a device comprising an operating member movable to actuate said device in one direction and also to accomplish an operative function to a reset position, power operated means for actuating said member in said one direction, a lever movable to operate said member and movable to a reset position, means at all times connecting said operating member and said lever for unitary movement, a compression spring having one end attached to said connecting means and having the other end attached to said lever at a point substantially intermediate the ends thereof for movement therewith, said spring applying a force to said operating member and to said lever to move said operating member in another direction to said reset position and to move said lever to said reset position independently of said power means, and said parts being adapted to increase the moment arm at which the force of said spring is applied to said operating member during the resetting movement to increase the torque applied to said operating member.

12. In a circuit breaker, a switch member movable to open and closed circuit positions, operating mechanism for said circuit breaker comprising an operating member operable to move said switch member to closed circuit position, a resettable latch releasably connecting said switch member to said operating member, a closing lever, means operatively connecting said closing lever to said operating member, restraining means for restraining said operating member and said switch member in closed circuit position, said restraining means also restraining said closing lever in an unoperative position, trip means operable in response to predetermined circuit conditions to effect release of said switch member from said operating member to cause opening of said breaker, said switch member during said opening movement effecting operation of said restraining means to permit movement of said operating member to a reset position to reconnect said operating member to said switch member, a compression spring having one end connected to said connecting means to apply a force to said operating member biasing said member in resetting direction, the other end of said spring being connected to said closing lever at a point intermediate the ends thereof for movement with said closing lever, said spring, said operating member, said lever and said connecting means being adapted to increase the moment arm with which the force of said spring is applied to said operating member during a resetting movement to increase the torque applied to said operating member, and power operated means for operating said closing lever to close said breaker.

13. In a circuit breaker, a switch member movable to open and closed circuit positions, operating mechanism for said circuit breaker comprising a pivoted operating member operable to move said switch member to closed circuit position, a resettable latch releasably connecting said switch

member to said operating member, a pivoted closing lever, said operating member and said closing lever being movable in opposite directions about their respective pivots, connecting means connecting the free ends of said closing lever and said operating member, means releasably restraining said operating member and said switch member in closed circuit position and for restraining said closing lever in an unoperative position, trip means operable in response to predetermined circuit conditions to release said switch member from said operating member to effect opening of said breaker, said switch member during opening movement operating said restraining means to permit movement of said operating member to a reset position to reset said latch, spring means biasing said operating member in resetting direction with a predetermined torque, said spring means having one end connected to said connecting means at a point adjacent the free end of said operating member and the other end connected to said closing lever at a point substantially intermediate the ends thereof, said parts being adapted to increase the moment of application of said torque to apply a greater torque to said operating member during the latter part of the resetting movement than at the be-

ginning of said resetting movement to reset said latch, and power-operated means for engaging and operating said closing lever and said operating member to close said breaker.
